UNITED STATES PATENT OFFICE.

CHARLES E. MILLIN, OF PROVIDENCE, RHODE ISLAND.

DESIGN FOR A LOCKET.

SPECIFICATION forming part of Design No. 12,904, dated April 25, 1882.

Application filed March 10, 1882. Term of patent 7 years.

To all whom it may concern:

Be it known that I, CHARLES E. MILLIN, of the city and county of Providence, and State of Rhode Island, have invented a new and useful Design for Lockets; and I do hereby declare that the following specification, taken in connection with the accompanying drawings, forming a part of the same, is a full, clear, and exact description thereof.

10 My design relates to a stone-set locket; and it consists in a locket having a convex face in which one or more stones are set flush with the surrounding rim.

15 Referring to the drawings, Figure 1 represents in perspective a locket having a convex face which is set with a single stone flush with the surrounding rim. Fig. 2 shows a similar locket, whose convex face is set with three stones flush with the surrounding rim

20 portions.

A A are the rim portions of the locket-face, and B is the stone or stones set therein. As shown in each figure, the contour of the stone-set face is convex, and the stones have the

same facial contour both longitudinally and 25 transversely as the surrounding rim portions, and are flush therewith.

The two halves composing the locket, as shown in the drawings, are hinged together at the top, and their sides are broken in outline; 30 but the said halves may be hinged at their sides, and said sides may be straight or unbroken without changing the characteristic feature of the design, which consists in a locket having a convex face with one or more stones 35 set therein flush with the surrounding rim portions.

What I claim as my invention, and desire to secure by Letters Patent, is—

The design herein described, consisting of a 40 locket having a convex face with one or more stones set therein flush with the surrounding rim portions.

CHARLES E. MILLIN.
